SIGNALING SYSTEM

Clarence E. Lomax, Chicago, Ill., assignor, by
mesne assignments, to Associated Electric Labo-
ratories, Inc., Chicago, Ill., a corporation of
Delaware

Application August 16, 1923, Serial No. 657,655

20 Claims. (Cl. 177—339)

This invention relates in general to signaling systems and its object, broadly stated, is to provide a new and improved signaling system for controlling vehicular traffic. More specifically, 5 the object of the invention is to provide a signaling system for controlling vehicular traffic in a narrow passage where the vision is obstructed, such as a one way tunnel, in which the signals can be operated from either along the line of 10 traffic or from a control station and restored individually only from the control station.

To accomplish the foregoing and other useful ends this invention comprises means which will be fully described in the specification which is to 15 follow, reference being had to the accompanying drawing, which shows diagrammatically the apparatus and circuits involved.

The apparatus to the right of the vertical dot and dash line is located in the tunnel while that 20 to the left is located at a control station. The former consists essentially of pairs of lamps of different color, in this case red and green, substantially as shown at L¹, L², L³, and L⁴, non-destructable or continuous use type alarm boxes B¹, 25 B², B³, and B⁴ containing push buttons, and telephone sets A¹, A², A³, and A⁴. The lamps at L¹ are located at the entrance of the one way tunnel to control the traffic about to enter; while those at L², L³ and L⁴ are located at intervals of approxi- 30 mately 500 feet along the tunnel. They are installed in the ceiling, or other conspicuous places, out of reach of persons in the tunnel so as not to be tampered with. The alarm boxes B¹, B², B³ and B⁴ and telephone sets A¹, A², A³ and A⁴, associated with the pairs of lamps L¹, L², L³ and L⁴, respectively, are located along the sides of the tunnel in an accessible place.

The apparatus located at the control station consists essentially of supervisory lamps L¹¹, L¹², 40 L¹³, and L¹⁴; non-lock re-set keys K¹, K², K³, and K⁴; non-lock trip keys K¹¹, K¹², K¹³, and K¹⁴; switching relays 1, 2, 3, and 4; generator G; buzzer Z and its associated equipment; telephone set A and its associated equipment.

45 Having briefly explained the purpose of the invention and the apparatus involved in carrying it out, the operation of the equipment may now be explained more in detail. For this purpose it will be assumed that an accident has occurred 50 between signals L³ and L⁴ and that an alarm is sent in from box B³.

When the person sending in the alarm pushes the button in the alarm box B³ the following circuit is opened at spring 42: Ground, spring 42 55 and its working contact, working contact of

spring 18 and said spring, armature 22 and its working contact, working contact of armature 25 and said armature, relay 3, and grounded battery. Relay 3, upon deenergizing, further opens the above traced circuit at armature 25; opens 60 at armature 21 the circuit of relay 2; closes at armature 29 a circuit for relay 5 by way of supervisory lamp L¹³; and transfers at armature 35 from a circuit including generator G and green lamp at L³ to one including the same generator 65 and red lamp at L³. Relay 5, upon energizing, closes at armature 11 a circuit for buzzer Z. Relay 2, upon deenergizing, further opens its circuit at armature 24; opens at armature 20 the circuit of relay 1; closes at armature 28 a circuit 70 for supervisory lamp L¹² in multiple with the circuit including supervisory lamp L¹³; and transfers at armature 34 from a circuit including generator G and green lamp at L² to one including the same generator and red lamp at L². Relay 75 1, upon deenergizing, further opens its circuit at armature 23; closes at armature 27 a circuit for supervisory lamp L¹¹ in multiple with the circuits including supervisory lamps L¹² and L¹³; and transfers at armature 33 from a circuit including generator G and green lamp at L¹ to one 80 including the same generator and red lamp at L¹.

From the above it will be seen that when an alarm is sent in from a box along the line of traffic the green lamps from there back are extinguished and red lamps lighted thus acting as a signal for traffic to stop; while the green lamps beyond are unaffected thus permitting the traffic to proceed. The buzzer Z is operated at the control station to notify the attendant that an alarm 90 has been sent in. Supervisory lamps (L¹¹, L¹², and L¹³) at the control station, corresponding to the red lamps lighted along the line of traffic, are lighted to advise the attendant of the location of the accident and keep him advised of the status 95 of the lamps along the line of traffic.

It will be assumed now that the person in the tunnel desires to converse with the attendant at the control station relative to the accident and uses the telephone set A³. It may be that the person in the tunnel is not familiar with the use of the alarm boxes, or there may be a ground on the line, possibly due to the accident, which prevents the signals from responding to an alarm sent in from Box B³. When he removes the receiver at station A³ a circuit is closed including relay 7; which relay, upon energizing, closes at armature 32 a circuit for lamp L by way of armature 31. Lamp L, upon lighting, notifies the attendant at A of the call. The attendant, upon 105 110

- removing his receiver, closes a circuit including relay 6; which relay, upon energizing, opens at armature 31 the circuit of the lamp L and extinguishes same. The talking circuit now being operative, the attendant converses with the calling party and receives the alarm information, whereupon they hang up their receivers and the circuit is restored to normal, all of which is in the well known manner.
- 10 The attendant at the station A, upon receiving the alarm information from the party at the station A³, operates the corresponding non-lock trip key K¹³; whereupon the green lamps are extinguished and the red lamps lighted at points 15 L³, L², and L¹, and the supervisory lamps L¹³, L¹², and L¹¹ are lighted, the same as when the alarm was sent in from box B³.
- To restore the alarm sending, signaling and supervisory circuits and equipment to normal 20 conditions the attendant at the control station operates the non-lock re-set keys K³, K² and K¹. For example, if he operates the key K³, a circuit is closed from ground, spring 14 and its resting contact, relay 3 to grounded battery. Relay 3 is 25 energized (its normal condition); prepares at armature 21 a circuit for relay 2 by way of spring 17 at trip key K¹² and spring 43 at alarm box B²; closes at armature 25 a locking circuit for itself by way of armature 22, spring 18 at trip key K¹³ 30 and spring 42 at alarm box B³; opens at armature 29 the circuit for supervisory lamp L¹³, thereby extinguishing same; and transfers at armature 35 from a circuit including generator G and red lamp at L³ to one including the same generator 35 and green lamp at L³. In a similar manner the operation of non-lock re-set keys K² and K¹ will restore their corresponding circuits and equipment to normal conditions. To restore all 40 circuits and equipment permanently to normal condition the re-set keys must be operated in the order named. After the last re-set key has been operated relay 5 deenergizes and opens at armature 11 the circuit of buzzer Z, thus restoring same to normal.
- 45 From the above it will be seen that the red lamps can be extinguished and the green lamps lighted along the line of traffic, to their normal conditions, only from the control station, and that each set of lamps can be operated independently 50 but can only be reset after the preceding lamps have been reset.
- The advantage of the arrangement whereby 55 the signals can be reset only from the control station and not from the right of way will readily be perceived. The alarm boxes are necessarily placed so that they are readily accessible to persons in the tunnel and if the signals could be reset from one of these boxes it might be done prematurely by some unauthorized person, with the 60 result of causing congestion or even another accident. The positive arrangement according to which the signals can only be reset in a definite order is also very desirable. If the signals L¹ could be reset prior to signals L², for instance, it 65 would permit traffic to enter the tunnel while vehicles were still being held up in front of signals L² and L³, thus causing congestion at these points. Traffic should be prevented from entering until the 70 conditions are such that the vehicles already in the tunnel can proceed and until they actually begin to do so. This result is secured by the positive circuit arrangement which prevents the locking up of a relay such as relay 1 until the preceding relay 2 has been locked up.
- 75 Having described my invention, what I con-

sider to be new and desire to have protected by Letters Patent will be pointed out in the appended claims.

What I claim is:

1. In a signaling system, a plurality of normally inactive "stop" signals spaced at intervals along a traffic route, a plurality of control devices also spaced along said route, means responsive to the operation of any device for rendering active all said stop signals which are located in one direction from the operated device, and means for maintaining such "stop" signals active after the operated device has been restored. 80
2. In a signaling system, a series of signals, means including a series of relays for controlling said signals, respectively, a normally closed circuit for each relay, whereby all of said relays are normally energized, contacts in each relay circuit except the last controlled by the next succeeding relay, whereby each relay on deenergizing will cause the deenergization of the preceding relay except the first, an individual energizing circuit for each relay, and contacts on each relay for closing its own normally closed circuit. 85
3. In combination with a plurality of signaling means spaced along a one way traffic passage, each of said means including means for indicating proceed and halt and normally indicating proceed, of means for operating the signals from stations adjacent the respective signaling means 90 to change the signal to indicate halt at the station at which the means are operated and to simultaneously cause a like change to occur at all the other signaling means in the direction from which traffic is flowing, and means partially 95 located at a central station and also including a part of said last named means for operating the signaling means. 100
4. In combination with a plurality of signaling means spaced along a one way traffic passage, 105 each of said means including means for indicating proceed and halt and normally indicating proceed, of controlling means for causing all signals preceding any desired one of the signals to change the indication from proceed to halt, said controlling means including a device individual to each of the signaling means located at a central station and also including a second device located adjacent to and individual to each signal for controlling the latter and, through a portion 110 of the controlling means, the preceding signals. 115
5. In combination with a plurality of signaling means spaced along a one way traffic passage, each of said means including means for indicating proceed and halt and normally indicating 120 proceed, of controlling means for causing all signals preceding any desired one of the signals to change the indication from proceed to halt, said controlling means including a device individual to each of the signaling means located at a central station and also including means located adjacent the respective signals, for controlling the circuits, and also including centrally located means for restoring the signals. 125
6. In combination with a plurality of signaling means spaced along a one way traffic passage, each of said means including means for indicating proceed and halt and normally indicating proceed, of controlling means for causing all signals preceding any desired one of the signals to 130 change the indication from proceed to halt, said controlling means including a device individual to each of the signaling means located at a central station and also including means located adjacent the respective signals, for controlling the circuits, and also including centrally located means for restoring the signals. 135
7. In combination with a plurality of signaling means spaced along a one way traffic passage, each of said means including means for indicating proceed and halt and normally indicating proceed, of controlling means for causing all signals preceding any desired one of the signals to 140 change the indication from proceed to halt, said controlling means including a device individual to each of the signaling means located at a central station and also including means located adjacent the respective signals, for controlling the circuits, and also including centrally located means for restoring the signals. 145
8. In combination with a plurality of signaling means spaced along a one way traffic passage, each of said means including means for indicating proceed and halt and normally indicating proceed, of controlling means for causing all signals preceding any desired one of the signals to 150 change the indication from proceed to halt, said controlling means including a device individual to each of the signaling means located at a central station and also including means located adjacent the respective signals, for controlling

- the circuits, and also including means individual to each of the signaling means and centrally located for restoring the signals.
7. In a signaling system, "stop" and "clear" signals located in pairs along a traffic route, a control station, a relay at said station for each pair of signals, means including a front contact on each relay for controlling the associated "clear" signal, means including a back contact on each relay for controlling the associated "stop" signal, an energizing circuit for each relay including a switch at the control station, a locking circuit for each relay including a normally closed switch at the control station and a normally closed switch on the traffic route, contacts on each relay included in its locking circuit, and contacts on each relay which are included in the locking circuit of an adjacent relay. 80
8. In a signaling system for use in a tunnel, a signal at the entrance of the tunnel, other signals spaced at intervals along the tunnel, manually operable switches located along the tunnel at the points where said other signals are located, means responsive to the operation of any switch for changing the indication of the associated signal and for also changing the indication at all other signals in the direction of the tunnel entrance, and means including a manually operable switch for each signal for restoring the same to normal. 95
9. A signaling system as set forth in claim 8, in which each signal comprises "stop" and "go" lights of different colors, and in which the indication of any signal is changed by extinguishing one light and lighting the other. 100
10. A signaling system as set forth in claim 8, in which the means for changing the indication of the signals includes relays which are located in a control station at one end of the tunnel. 105
11. In a traffic control system for a tunnel or similar traffic route, a control station, means controlled through said station from any one of a plurality of control points along the tunnel for stopping traffic at that point, a portion of said means being controlled automatically from the control station when traffic is stopped at any control point for stopping traffic at all other control points between such control point and the tunnel entrance, and means controlled exclusively at the control station for starting traffic movement at any control point at which it has been stopped. 115
12. In a traffic signaling system, a plurality of traffic controlling signals located along a traffic route, a plurality of relays at a control station, circuits over which said relays control said signals, a locking circuit for each relay which maintains it energized, contacts on each relay included in its locking circuit, manually operable switches located along the traffic route for opening said locking circuits, manually operable switches at the control station for use alternatively in opening said locking circuits, contacts on each relay for breaking the locking circuit of an adjacent relay, and means including a manually operable switch at said control station for each relay for reenergizing the same after it has de- 125 energized responsive to the opening of its locking circuit. 130
13. In a traffic signaling system, a series of normally inoperative signals indicating "stop" when operated located at intervals along a traffic route, a central station, control means for said signals including an operating device adjacent each signal, a second operating device for
- each signal at the central station, and means interconnecting said devices and signals, for operating any signal to maintain a "stop" indication upon the operation of its adjacent operating device or the corresponding central station device and for operating all of the other signals in the series, in one direction from the first named signal, to also indicate "stop", except on operation of the end signal of the series in the direction stated. 135
14. In a traffic signaling system, a series of normally inoperative signals indicating "stop" when operated located at intervals along a traffic route, a central station, control means for said signals including an operating device adjacent each signal, a second operating device for each signal at the central station, and means interconnecting said devices and signals, for operating any signal to maintain a "stop" indication upon the operation of its adjacent operating device or the corresponding central station device and for operating all of the other signals in the series, in one direction from the first named signal, to also indicate "stop", except on operation of the end signal of the series in the direction stated. 140
15. In a traffic signaling system, a series of signals located at intervals along a traffic route, a central station, control means for said signals including an operating device for each signal at the central station, and means, interconnecting said devices and signals, for operating any signal to display and maintain a stop indication upon the actuation of its operating device and for operating all of the other signals in the series in one direction from the first named signal to also display a stop indication. 145
16. In a traffic signaling system, a series of normally operative signals indicating "clear" located at intervals along a traffic route, a central station, control means for said signals including an operating device adjacent each signal, a second operating device for each signal at the central station, and means, interconnecting said devices and signals, for restoring any signal upon the operation of its adjacent operating device or the corresponding central station device and for restoring all of the other signals in the series, in one direction from the signal first restored, except on the restoration of the end signal of the series in the direction stated. 150
17. In a traffic control system, a series of traffic controlling devices located at intervals along a traffic route, a central station, control means for said devices including a switch adjacent each device, a second switch for each device at the central station, and means interconnecting said switches and control devices, for operating any control device upon the operation of its adjacent switch or the corresponding central station switch and for operating all the other control devices in the series, in one direction from the first operated control device, except on the operation of the end control device of the series in the direction stated. 155
18. In a signaling system, a plurality of signaling devices located at intervals along a traffic route, said devices indicating either "stop" or "clear", means for causing said signaling devices to normally indicate "clear", a plurality of control devices also located at intervals along said traffic route, means responsive to the actuation of any control device for causing all signaling devices located in one direction from the actu- 160

ated control device to change their indication from "clear" to "stop", and means for maintaining all said last mentioned signaling devices in changed condition after the actuated control device has been restored.

19. In a signaling system for handling traffic passing in one direction along the traffic route, a plurality of signaling devices located at intervals along said traffic route, said devices indicating either "stop" or "clear" to oncoming traffic, means for causing said signaling devices to normally indicate "clear", means for changing the indication of said signaling devices, means effective when the indication of any signaling device is changed for automatically changing the indication of all other signaling devices located in the direction from which the traffic is coming, and means for restoring to normal any changed signaling device at will, while maintaining the re-

20

maining changed signaling devices in changed condition.

20. In a signaling system, a plurality of signaling devices located at intervals along a traffic route, said devices indicating "stop" or "clear", means for causing said signaling devices to normally indicate "clear", means for changing the indication of said signaling devices, said means located at a common control station and including a separate control device for each signaling device, means including circuit arrangements such that the operation of any control device except the first not only changes the indication at the associated signaling device but also changes the indication at one or more of the other signaling devices, and means for maintaining the indication at such signaling devices changed after the operated control device has been restored.
